GUN BARREL COOLING MEANS

Charles E. Balleisen, Philadelphia, Pa., assignor
to the United States of America as represented
by the Secretary of War

Application February 4, 1942, Serial No. 429,496

10 Claims. (Cl. 89—14.1)

(Granted under Title 35, U. S. Code (1952),
sec. 266)

1

The invention described herein may be manufactured and used by or for the Government for governmental purposes, without the payment to me of any royalty thereon.

This invention relates to means for introducing fluid into the interior portions of the barrel of a firearm.

An object of this invention is to provide means for injecting fluid into the barrel of an automatic firearm immediately after each round of ammunition is fired.

Another object of this invention is to provide a compact valve, especially adapted to be used with a firearm for introducing a predetermined amount of fluid into the barrel of an automatic firearm immediately after each round of ammunition is fired.

Another object of this invention is to provide means for injecting cooling fluid into the barrel of an automatic firearm in such a quantity that the cooling fluid which may be water, flashes into the gaseous state and maintains the barrel at a safe operating temperature.

This invention has specific application to a barrel of .50 caliber but it is understood that this invention may be applied to barrels of greater and smaller caliber. Sufficient fluid, preferably water, is introduced in the gun barrel so as to maintain the final steady state temperature of the gun barrel under continuous operation at approximately 300° F. when the gun is operated continuously; however, this temperature may be subject to variation and the only apparent limitation on that temperature appears to be based on the following considerations; that at the higher range the temperature should not be destructive to the barrel material and at the lower range the temperature should be high enough to vaporize the cooling fluid which is introduced.

In the cooling of automatic guns by the particular means disclosed herein it is fundamental to realize that the valve for introducing the fluid into the gun barrel should be capable of being placed in those positions where the introduction of fluid will produce the greatest cooling effect. Since the time available for injection of the fluid into the barrel between rounds is approximately .02 second and since a few cubic centimeters of water must be introduced into the barrel of a .50 cal. gun in that short period of time, it follows that a quick responsive valve is necessary and that it should be so positioned on the gun barrel that one or more conduits through the barrel wall will not seriously alter the mechanical strength of the barrel.

2

In general, there are four methods of operating an inlet valve for the injection of a cooling liquid into a barrel of an automatic-gun during the period of ammunition extracting and loading.

5 These four methods may be classified as follows:

1. Recoil
2. High pressure
3. Low pressure (muzzle) gas
4. Bullet or muzzle blast

10 The fourth method is generally dismissed as being inferior to the others. Means are disclosed herein for carrying out any one of the first three methods.

15 The first three methods outlined above are beset with advantages and disadvantages. In general, the recoil method has the following advantages: (1) mechanical motion is directly available, (2) mechanism is simple, and (3) there is an inherent controlled time delay; the disadvantages are as follows: (1) the operating reserve of the gun is reduced, and (2) there is a danger of flooding the barrel before firing.

20 In general, the second method incorporating high pressure gas has the following advantages: (1) the mechanism is simple, and (2) there is no appreciable energy extracted from the gun; the disadvantages are as follows: (1) mechanical motion must be produced, (2) a time delay must be provided, and (3) an adequate seal preventing the loss of gas must be provided.

25 In general, the third method incorporating low pressure gas has the following advantages: (1) no appreciable energy is extracted from the gun, and (2) an inherent time delay is introduced; 30 the disadvantage is as follows: (1) the mechanism is complicated.

35 The specific nature of the invention as well as other objects and advantages thereof will clearly appear from a description of a preferred embodiment as shown in the accompanying drawings in which:

40 Fig. 1 is a side view of a portion of a Browning automatic machine gun with a fluid valve and its actuating mechanism mounted thereon. The rear position and correspondingly the fluid valve allows passage of fluid;

45 Fig. 2 is a plan view of the assembly shown in Fig. 1;

50 Fig. 3 is an end view of the fluid valve and its actuating mechanism taken substantially on line 3—3 of Fig. 2; the pertinent portions of the firearm are shown dotted;

55 Fig. 4 is a sectional view taken substantially on line 4—4 of Fig. 3;

Fig. 5 is a side view of a portion of a gun barrel with a fluid valve housed therein; the valve is adapted to be actuated by pressure developed in the barrel bore synchronously with the rate of fire of, for example, a Browning machine gun;

Fig. 6 is a section through the fluid valve and barrel taken substantially on line 6-6 of Fig. 5; the valve is shown in its normal position or furthermost down position;

Fig. 7 is a section similar to the section of Fig. 6 but in this instance the cup shaped valve member 13 has been displaced from its normal position up to its highest position due to ammunition gas pressure on the bottom of cup shaped member 13;

Fig. 8 is a section similar to the section of Fig. 6 but in this instance the cup shaped valve member 13 has receded from its highest position of Fig. 7 to the position shown wherein cooling fluid may flow from channel 18 or 19 into the barrel bore;

Fig. 9 is a section taken substantially through the bottom of the cup shaped member on line 9-9 of Fig. 8;

Fig. 10 is a longitudinal section taken substantially through the center of the barrel and through the center of valve actuating mechanism which is responsive to ammunition gas pressure at the muzzle of the firearm. The mechanism in this instance is shown in its most forward position;

Fig. 11 is a section similar to the section of Fig. 10 but in this instance the valve mechanism is in its extreme rear position corresponding to 35 valve opening position;

Fig. 12 is a section taken substantially on line 12-12 of Fig. 10;

Fig. 13 is an end view taken substantially on the direction of line 13-13 of Fig. 11.

Figures 1-4 relates to a valve operated in accordance with method 1 listed above, i. e. by the motion of one of the gun parts which moves due to recoil forces imparted thereto. The particular mechanism shown in these figures has special application to a Browning machine gun of the type disclosed in the Browning Patents 1,293,021 and 1,628,226 and is particularly designed to be installed on those guns. It is understood, however, that this particular type of valve operating mechanism may be applied to other guns having parts which move in recoil. The elements disclosed in Figures 1-4 are given the same reference numerals as those ascribed to corresponding elements in the Browning Patent 1,293,021 and reference is had to the disclosure in that patent; it is understood that the operation of the Browning machine gun as disclosed in that patent is well known since that particular gun has found universal use, especially in the United States. The parts added to the Browning machine gun in order to carry out this aspect of my invention are given reference numerals greater than 100.

A nozzle 101 with an integrally formed valve housing 102 is centrally and stationarily mounted between the side plates *a*, *a* of the gun by means of screws 110 (Fig. 3) and arms 111 such that the nozzle is in the vertical plane with the gun bore and directed so as to guide a jet of cooling fluid into the cartridge receiving chamber barrel B. The arms 111 and screws 110 are, of course, arranged so as to not interfere with the normal operation of the gun.

The valve housing 102 is formed from a solid

cylindrical block and has a hole 104 (Fig. 1) therethrough in line with the hole in nozzle 101 and the high pressure supply conduit or passage 103, and also a hole 105 (Fig. 3) therethrough 5 having its axis substantially perpendicular to the axis of hole 104. Axially movable rod or closure member 106 with reduced section or portion 109 passes through hole 105 and is adapted to normally allow the flow of cooling fluid from conduit 103 to nozzle 101 due to the biasing action of spring 107 which is mounted between housing 102 and a flange 108 on the end of rod 106; when the rod 106 is moved to the right (Fig. 3) by means to be discussed later, the reduced portion 15 109 of rod 105 is moved out of its normal aligned position with hole 104 and fluid is then prevented from passing from supply conduit 103 to the nozzle 101. Rod or closure member 106 is moved to the right (Fig. 3) due to movement of the breech bolt E because of the interconnecting members: cam member 115, lever 116, pivot rod 117 and lever 118. Cam member 115 projecting through slot 122 in one of the side plates *a* is adapted to contact the upper right hand corner 25 of the breech bolt E (Fig. 3) and to be moved to the right as the bolt moves to the breech closing position; this movement of cam member 115 causes levers 116, 118, which are rigidly connected to pivot rod 117, to rotate and to move the valve rod 106 to the right (Fig. 3). Shoulder 116s on arm 116 provides a stop for movement of cam 115 relative to plate *a*.

When the cam 115 is in its furthermost right position with reference to Fig. 3 the flow of fluid to the barrel chamber B is prevented. The time during which the fluid valve is in open position as related to the movement of the breech bolt E is indicated by the limits 120, 121 (Fig. 2); it is understood that fluid is allowed to be projected into the barrel chamber when the forward edge of the breech bolt E is on or between the limits of 120, 121. Spring 107 is placed under compression so that shoulder 116s on arm 116 positively abuts against side plate *a* when the bolt E is on or between the limits 120, 121. Arms 116, 118 are made sufficiently long to bring about the above described operation and also so that the pivot rod 117 is carried forward sufficiently to clear operating parts of the gun. A bearing block 130 for rod 117 is secured to the right side plate *a* of the gun by means similar to screws 131. Collar 132 on rod 117 abuts against the bearing block 130 so as to support some of the weight of the mechanism.

It is thus seen from Figs. 1 and 2 that cooling fluid is injected into the gun barrel B so long as the breech bolt E is in open position and is retracted sufficiently to allow the tip 125 of an ammunition round to clear the chamber of barrel B, i. e., the clearance between the round tip 125 and chamber of barrel B is somewhat greater than the distance between limits 120, 121.

A valve adapted to be incorporated in a high pressure gas system described as method 2 is shown in Figs. 5-9. The valve described in these figures has an inherent time delay therein and seals well against loss of gas from the barrel B. The valve proper does not project beyond the normal cylindrical confines of the barrel and the working parts thereof are confined by the wedge shaped member 10, which fits into a cooperating groove 11 in the barrel B. The valve consists essentially of a spring 12, a cup-shaped member or valve 13 having three ports 13a, 13b, 13c therein, and a ring or check 14 which is fric-

tionally held by the surrounding interior cylindrical wall 15 of the barrel B. Ring 14 may partake of an oversized split resilient ring such as a conventional automobile piston ring. Ring 14 is moved by the cooperating shoulders 13e, 13f on the cup-shaped member 13 as it moves up and down in the barrel hollow portion or valve chamber 16 due to the gas pressure within the bore 17 of barrel B or due to the action of compression spring 12.

Cooling fluid, for instance water, under high pressure of approximately sixty pounds per square inch, is introduced into the barrel bore 17 through barrel channels or pair of passages 18 and 19, channels 13a, 13b, 13c and barrel channel 20. Channels 13a, 13b, 13c have the common centrally disposed channel 13d in communication therewith.

In the normal position, Fig. 6, the channels 18, 19 are closed by frictionally held ring 14 so that no cooling fluid flows into the barrel. When a shell is fired a large pressure will be built up in the barrel bore 17 causing the cup-shaped member 13 to move upward against the action of spring 12 and causing shoulder 13f to engage ring 14; further movement of member 13 will cause displacement of ring 14 and place shoulder 13f in a position where it seals barrel ports 18, 19. Thus, no fluid will flow into the barrel as the cup-shaped member 13 moves upward to its highest position shown in Fig. 7. As cup-shaped member 13 moves downward from its highest position due to loss of pressure caused by the emergence of the fired projectile from the barrel and due to the action of compression spring 12, ring 14, which is frictionally held by barrel wall 15, will remain stationary and cooling liquid will flow from barrel channels 18, 19 to the barrel bore 17 (Fig. 8). Further downward movement of cup-shaped member 13 will cause shoulder 13e to engage ring 14 and bring it into the port closing position shown in Fig. 6. The elasticity of spring 12 and the amount of friction between ring 14 and barrel wall 15 will determine to a large extent the time delay involved before cooling fluid may be injected into barrel bore 17.

It is preferred to inject the cooling fluid into the barrel bore after the cartridge shell is extracted from the barrel bore and before a new cartridge is inserted into the bore; in that case the time for fluid flow is approximately .02 second. The appropriate time delay and time during which cooling fluid flows may be subjected to wide variation by the particular design of the spring 12, cup-shaped member 13, and frictionally held ring 14.

A mechanism adapted to be incorporated in a low pressure gas operated system, for instance, a mechanism operated by the muzzle gases of a gun, is shown in Figs. 10-13.

In the above mentioned figures the flow of cooling fluid follows the following path: from a source of pressure (not shown) of approximately 75 pounds per square inch through inlet or passage 30a in valve housing 30, valve chamber 31, channels 32a, 32b, 32c in the movable portion 32 of the gas operated valve, port 33 in the valve housing 30, and then through barrel opening 34 into the bore 35 of the barrel 36.

Movable portion 32 of the valve is normally biased in its closed position by means of compression spring 37 and is moved to its open position when muzzle gas pressure acts on piston 38.

Nut 39 serves to confine the biasing spring 37 in the valve housing as well as to jam the op-

posite end of sleeve 40 against packing 41 so as to prevent fluid leakage past the exterior cylindrical wall of the integrally formed shank or valve closure member 32f which abuts against the free end of spring 37.

Nut 42 and packing 43 serve to prevent fluid leakage out of the valve housing 30 at the place where piston rod 38' emerges from the valve housing.

- 10 The piston chamber 44 for piston 38 is formed in a substantially cylindrical block 50 which has a tapered portion 45 screwable on the end of barrel 36, a hole 46 in alignment with the barrel bore, and a tapped portion 47 in alignment with 15 the piston chamber 44 for the reception of plug 48. The cylindrical block 50 is screwable on barrel 36 to such an extent that a clearance 51 is provided between the end of the barrel and the cylindrical block 50. Muzzle gases due to the 20 burning of the ammunition in the gun flow through the clearance 51 into the piston chamber 44. A pin 52 which passes through cooperative grooves in the barrel and cylindrical block 50 maintains those two elements in fixed position.
- 25 The piston 38 may be provided with a ring or packing 53 so as to prevent loss of pressure past the outer wall of the piston.

The integrally formed valve and spring housing 30 may be fastened to the barrel 36 by means of screws 54, by welding or other similar means.

In all three arrangements disclosed herein a predetermined quantity of vaporizable fluid is injected into the gun barrel, the exact amount being determined by the applied fluid pressure, size of orifices leading into the barrel and the time interval during which the particular valve is open. Since the last two mentioned factors are fixed to a certain degree the most convenient manner in which the exact amount of fluid may be injected in the gun barrel resides in controlling fluid pressure by means well understood.

I claim:

1. A cooling arrangement for a gun having a barrel, means forming a fluid passage in the barrel leading to the barrel bore, said barrel having a circular hollow portion therein in communication with the fluid passage, a spring biased member in said hollow portion and responsive to barrel gas pressure, a pair of spaced shoulders on the member, a ring frictionally engaging the walls defining the hollow portion and adapted to close said passage, said ring being disposed between said shoulders.
- 45 2. The same as in claim 1 characterized in that the spring biased member is within the normal confines of the barrel, and a wedge having a tongue and groove connection with the barrel for maintaining said member in the barrel.

3. A cooling arrangement for a gun, said cooling arrangement comprising a barrel formed with a passage therethrough communicating with the bore of said barrel for admitting fluid under pressure to said bore, a valve device slidably mounted for longitudinal movement within a 60 valve chamber intercepting said passage, said valve device in said chamber constructed and arranged to be moved away from said bore by gas pressure within said bore while maintaining said passage intercepted, and a spring within said barrel for moving said valve device toward the bore and into passage-opening position upon subsidence of the gas pressure within said bore.
- 65 4. A cooling arrangement for a gun, said cooling arrangement comprising a barrel formed with a passage therethrough communicating with the

bore for admitting fluid under pressure to said bore, said barrel having a valve chamber intercepting said passage, a spring biased valve member in said chamber having a fluid passage therethrough and operable by the barrel gas pressure, and a second member surrounding the first mentioned member and frictionally held between the said first member and the wall of said chamber and moved by said valve member toward the bore and into position opening said passage to flow of fluid to the bore of the barrel upon the subsidence of the gas pressure in the bore.

5. In combination with the barrel of an automatic rapid fire gun, said barrel having a bore, a chamber formed in the wall of said barrel, there being a first passage in said wall adapted to connect said chamber with a source of pressure fluid, there also being a second passage in said barrel from said chamber to said bore, and valve means in said chamber normally intercepting communication between said passages and responsive to change in gas pressure in said bore transmitted through said second passage, to connect said first and second passages after a cartridge has been fired and before the next cartridge has been inserted into said barrel.

6. In combination with a gun barrel having an axial bore, a valve chamber, and first and second passages leading respectively from a source of fluid pressure to said chamber and from said chamber to said bore, valve means adapted to be moved by gas pressure in said bore from a first to a second position, spring means urging said valve means into said first position, and means coacting with said valve means to place said passages in communication on initial movement of said valve means from said second to said first position and then to cut off said communication.

7. In a cooling device for a gun barrel, said barrel having a valve chamber and first and second passages leading, respectively, from a source of pressure fluid to said chamber and from said chamber to the bore of said barrel, a valve movable in said chamber from a first position to a second position, said valve having a port adapted to place said first and second passages in communication, said valve being adapted to be moved to said second position by gas pressure in said bore, spring means urging said valve to said first position, and check means moved by and in response to movement of said valve to cut off communication between said passages except only while said valve is moving from said second to said first position.

8. In a cooling device for a gun barrel having a valve chamber and first and second passages leading respectively, from a source of pressure fluid to said chamber, and from said chamber to the bore of said barrel, a valve slidable in said chamber between first and second positions and having a port adapted to place said passages in communication, means urging said valve into said first position, said valve being moved to said second position by and in response to gas pressure in said bore, and a check slidably associated with said valve and coacting therewith and movable

thereby, to cut off said first passage from said port when said valve is moving from said first to said second position, and to open said first passage to said port when said valve is moving from said second to said first position.

5 9. In a system for the fluid cooling of a gun barrel, a cylindrical valve chamber associated with said barrel, there being a first passage adapted to connect said chamber with a source of pressure fluid and a second passage connecting said chamber with the bore of said barrel, a piston valve reciprocably fitting said chamber and having a ported circumferential channel adapted to connect said passages, said valve being movable by gas pressure in said bore from a first to a second position, spring means urging said piston into said first position, and a check ring fitting said channel and frictionally engaging the walls of said chamber, said ring being reciprocable on and moved by, said piston with lost motion and cutting off said first passage from said second passage when said valve is moving to said second position and clearing connection between said passages when said piston is moving toward said first position under the action of said spring means.

10 10. In a liquid cooling system for a gun barrel having a cylindrical valve chamber formed in its wall, a first passage extending from the wall of said chamber substantially midway of its length and adapted to communicate with a source of cooling liquid under pressure, and a second passage extending from one end of said chamber to the bore of said barrel, said system comprising, a piston valve reciprocably fitting said chamber and having a circumferential channel in its periphery, ported for communication with said second passage, said piston valve being movable by gas pressure in said bore from a first position in which said channel is in agreement with said first passage, to a second position in which said piston valve partly cuts off said first passage, a ring fitting and having lost motion within said channel and frictionally engaging the wall of said chamber, said ring and piston valve coacting to cut off said first passage when said valve is in said second position, and spring means urging said valve to said first position whereby on decrease in gas pressure in said bore, said valve first opens said first passage to communication with said second passage and thereafter moves said ring to cut off said communication.

CHARLES E. BALLEISEN.
